United States Patent

Des. 234,448
Patented Mar. 11, 1975

234,448

GOBLET OR SIMILAR ARTICLE

Walter B. Achenbach, Toledo, Ohio, assignor to Owens-Illinois, Inc., Toledo, Ohio

Filed July 9, 1973, Ser. No. 377,595

Term of patent 14 years

Int. Cl. D7—01

U.S. Cl. D7—13

FIG. 2

FIG. 1

FIG. 3

FIG. 4

FIG. 6

FIG. 5

FIG. 7

FIG. 8

FIG. 1 is an elevational view of a goblet or similar article showing my new design in the size and proportions of a water glass;

FIG. 2 is a top plan view thereof;

FIG. 3 is a bottom view thereof;

FIG. 4 is an elevational view of a goblet or similar article showing my new design in the size and proportions of a cocktail glass;

FIG. 5 is an elevational view of a goblet or similar article showing my new design in the size and proportions of an on-the-rocks style glass;

FIG. 6 is a top plan view thereof;

FIG. 7 is a bottom view thereof;

FIG. 8 is an elevational view of a goblet or similar article showing my new design in the size and proportions of an old-fashioned glass.

I claim:

The ornamental design for a goblet or similar article, as shown and described.
